(57) **CLAIM**

The ornamental design for a carrier for transporting foods, as shown and described.

DESCRIPTION

FIG. 1 is a top, front, and right perspective view of a carrier for transporting foods of my design;

FIG. 2 is a right side view thereof;

FIG. 3 is a left side view thereof;

FIG. 4 is a front side view thereof;

FIG. 5 is a back side view thereof;

FIG. 6 is a top view thereof; and,

FIG. 7 is a bottom view thereof.

The broken lines shown represent environmental subject matter and form no part of the claimed design.
